UNITED STATES PATENT OFFICE.

OTTO KENITZ AND GEORG DEBROWSKY, OF PASSAIC, NEW JERSEY.

CURTAIN-BRACKET.

1,022,319.

Specification of Letters Patent.

Patented Apr. 2, 1912.

Application filed May 9, 1911. Serial No. 625,950.

To all whom it may concern:

Be it known that we, OTTO KENITZ and GEORG DEBROWSKY, citizens of the United States, residing at Passaic, in the county of Passaic and State of New Jersey, have invented new and useful Improvements in Curtain-Brackets, of which the following is a specification.

This invention relates to curtain brackets and its object is to provide an adjustable device in which the curtain roller may be journaled and supported after the arms are adjusted for same and at the same time brackets are adopted in connection with the device for the support of curtain rods as will be more fully described in the following specification, set forth in the claims and illustrated in the drawings, wherein—

Figure 1 is a perspective view of a pair of brackets ready for use. Fig. 2 is a plan view of same partly in section.

The invention consists of brackets 5 secured to the window frame by means of the threaded studs 6, and these brackets are adapted to lie parallel with the window frame and have serrations 7 on their inner and outer faces. The outer ends of the brackets are perforated for the reception of the screw threaded ends 8 of the curtain rod brackets 9, which may be screwed into the window frame and through the perforation. The object of these screws is to prevent the bracket from turning and at the same time to force the end of the bracket 35 inward in order to secure the inner ends 10 of the arms 11, which are provided with openings to fit over the brackets 5. These arms 11 are made in pairs, one having a perforation 12 and the other a slot 13 for the reception of the trunnions on the curtain roller. When it is desired to adjust these arms the screw 8 is loosened and the arm is moved along the bracket to the desired point when the screw is again tightened so as to prevent the movement of the arm along the bracket and secure its location at a desired point.

The whole bracket 9 may be made of wire and screwed into the window frame through the perforation in the end of the bracket. 50 Its outer end is semi-circular and it terminates in the upright pin 14, which is adapted to enter a hole in the outer end of the curtain rod. At the same time this bracket may be used to tighten the bracket 5 so that the 55 arm 11 may be adjusted thereon.

It is obvious that the device may be modified and the parts otherwise arranged without departing from the essential features above described.

What we claim as new and desire to secure by Letters Patent is—

1. In curtain brackets, the combination with brackets having serrated inner and outer sides, of an arm adjustable along the 65 bracket and having attaching means, and a curtain pole hook screwed into the end of the bracket and adapted to prevent the removal of the arm.

2. In a curtain bracket, the combination 70 with brackets having a threaded stud at one end and a perforation at the other, of serrations on the inner and outer faces and a perforated arm carried by the brackets and having a tooth to engage the serrations, and 75 a curtain pole support adapted to pass through the perforations at the outer end of the bracket to secure the arm in place.

3. In curtain brackets, the combination with brackets having serrated sides and a 80 perforation at one end, of a threaded stud at the other end, arms adapted to fit the brackets and having a tooth for the serrations, and threaded curtain pole supports adapted to pass through the perforation at 85 the end of the bracket and having a vertical pin to fit the pole.

In testimony whereof we affix our signatures in presence of two witnesses.

OTTO KENITZ.
GEORG DEBROWSKY.
